UNITED STATES PATENT OFFICE.

ERNEST LESLIE RANSOME, OF CHICAGO, ILLINOIS.

REFUSE-DESTRUCTOR.

SPECIFICATION forming part of Letters Patent No. 545,975, dated September 10, 1895.

Application filed October 10, 1894. Serial No. 525,530. (No model.)

To all whom it may concern:

Be it known that I, ERNEST LESLIE RANSOME, a citizen of the United States, residing at Chicago, in the county of Cook and State 5 of Illinois, have invented certain new and useful Improvements in Refuse-Destructors; and I do hereby declare that the following is a clear, exact, and full description of the invention, which will enable others skilled in 10 the art to which it appertains to make and use the same.

My invention relates to that class of furnaces known as "refuse-destructors," and is for the purpose of automatically breaking up 15 and discharging the clinkers and ashes produced therein.

I attain these objects by the mechanism illustrated in the accompanying drawings, in which--

20 Figure 1 is a vertical section of my improved furnace. Fig. 2 is a horizontal section through the discharge-openings. Fig. 3 is a side elevation of one of the vertical beams in part, showing some of the cross-beams in section. 25 Fig. 4 is an elevation of two vertical beams in part and their connections as viewed from the inside of the furnace. Fig. 5 is a bottom view of the eccentric, showing position of sweep; and Fig. 6 is a detail of the sweep.

30 The furnaces to which I prefer to apply my improvements are circular on plan and continuous in operation. They have tall solid walls and when working contain a great mass of burned matter. They are driven by an 35 air-blast and are of the type described by me in Letters Patent Nos. 524,687 and 524,688, both dated August 14, 1894. In burning refuse in such a furnace enormous clinkers are frequently formed, such as defy all ordinary

40 methods of removal. At other times, owing either to the changeable character of the refuse or to the lower temperature at which it has been burned, smaller clinkers and an abundance of dust and ashes are formed. A 45 successful apparatus for the removal of this material must be capable of handling it under all the varied conditions in which it is present. Such an apparatus was invented and patented by me under Letters Patent No. 524,688, of 50 August 14, 1894; but a difficulty exists in applying this patented invention to furnaces beyond ten feet in diameter--viz., the con-

struction and operation of a revolving grate of sufficient strength to endure the strain to which it would be subjected in breaking up 55 one of the enormous clinkers that are liable to come upon it.

By my present invention I overcome this difficulty by dispensing with the grate and its auxiliaries and substituting the following: 60 Upon the bottom of the furnace or hearth A a traveling discharger B rests loosely. It is moved eccentrically by eccentric C, which fits and works within it. This eccentric is carried upon bearing D, and it is driven by pinion E, power being furnished through shaft F. The hearth, by preference, slopes downwardly from within the circular area always covered by the base of the discharger to the beams G, as shown at A'. H is a channel for 70 the reception of such ashes as may creep in between the discharger and hearth in the working of the latter. This ash is swept out of the channel by the sweep H' into the sub-way I, through which it falls into chamber N, 75 from which it is removed at intervals. The walls of the furnace K rest upon a series of vertical beams G, which are strongly embedded into or attached to the hearth. To the vertical beams G are attached horizontal 80 beams G'. All these beams are by preference fitted with cutting-edges on their interior faces, as at G². Surrounding the hearth A is a circular traveler L. This may be of any suitable known variety. 85

The furnace is operated as follows: Clinkers are placed inside the furnace until the desired height for the fire is reached, when the fire is lighted, or the fire is started upon the hearth and fed until it has burned upward to 90 the desired height, say, at M. The air-blast is forced into furnace-chamber O, which is an air-tight chamber surrounding the working apparatus described herein, and finds its way upward to the fire by passing between beams 95 G and G' and through the mass of intervening clinkers. As soon as the fire is burning normally at the proper level it is kept well supplied with fuel from above through feed-pipe N and maintained at the right height by 100 the regulated withdrawal from below of the clinkers and ashes upon which it rests. This column of clinkers and ashes supporting the fire rests upon the hearth and discharger and

their withdrawal or discharge is accomplished as follows: Being set in motion by the eccentric C, the discharger B in its eccentric movement thrusts the clinkers and ashes outwardly, 5 thereby breaking up the large clinker-bodies and crushing the mass against the beams G and G' and driving a portion thereof through the openings between them. This discharge is continuous while the motion of the dis-
10 charger B is maintained, for as fast as a por-
tion of the contents of the furnace is thus dis-
charged the mass of clinker and ashes de-
scending by gravity follows on behind and sup-
plies the place of that which has been dis-
15 charged. The material discharged falls into
the circular conveyer L and is delivered there-
from at any desirable point by any of the
usual methods. The "discharger" B is by
preference conical or pyramidal. The sides
20 thereof may be smooth, roughened, toothed,
or stepped. Instead of moving it eccentrically
it may be made of irregular perimeter,
oblong, oval, or triangular on plan and be
driven eccentrically or with a gyratory or re-
25 ciprocal movement; but such alternatives are
not so desirable as the method described in
full. By extending the hearth out farther, so
as to give footing to the extended angle of
repose of the ashes that would be occasioned
30 by the removal of the cross-beams G', the lat-
ter could be omitted in cases where the in-
creased size of the lumps discharged, due to

such omission, would not be objectionable.
By sloping the hearth less power is required
for the discharge; but in cases where economy 35
in height is of more importance than economy
of power this slope can be omitted.

Disclaiming any rights to the use of the air-
tight blast-chamber O, so far as this present
invention is concerned, 40

What I claim as my invention, and desire
to secure by Letters Patent, is—

1. In combination with a conical discharger
mounted upon and operated by an eccentric,
a surrounding cage consisting of vertical and 45
horizontal bars against which the said dis-
charger crushes large clinkers and between
which it forces smaller pieces and ashes.

2. In a refuse burning furnace, a hearth
over the top of which clinkers are crushed 50
and discharged from said furnace; a central
chamber within said hearth for providing
space within which is placed the supporting
and driving mechanism for the crusher, a
channel in the upper face of said hearth and 55
surrounding said central opening for catch-
ing dust and ashes, and a sweep operated by
the driving mechanism for discharging ac-
cumulations from said channel into a subway
beneath.

ERNEST LESLIE RANSOME.
